Corporation, South Bend, Ind., a corporation of
Delaware

Application December 26, 1940, Serial No. 371,742

11 Claims. (Cl. 89—1)

1

This invention relates to guns, and more particularly to an automatic system for charging guns.

In many types of guns the loading operation is performed by the reciprocation of a breech bolt. This is particularly true of automatic guns such as machine guns or automatic cannon. In automatic guns the reciprocation of the breech bolt is accomplished by power developed by the firing of a shell, and the firing of one shell ejects its empty cartridge and places the succeeding shell in the gun breech ready for firing. If, however, one of the shells is a dud and fails to fire there is no reciprocation of the breech to eject the dud and insert a fresh shell. Such a gun is described as a jammed gun, which gun is thereafter unable to fire automatically. Also, the moving parts of an automatic gun may become stuck or pinched so that they are unable to operate automatically and such a gun is also termed a jammed gun. In any event, the only way to place a jammed gun in an operating position is to reciprocate the breech bolt by auxiliary means.

In the past it has been customary to reciprocate the sliding parts of a jammed gun by hand. When the gunner is remote from the gun, as the pilot of an airplane having guns in the wings, cables and other operating mechanism have to be supplied for this purpose. There are several drawbacks, however, to hand freeing of a jammed gun. In the larger calibre guns and cannons now in use it is very difficult to reciprocate the moving parts manually. Further, if the gunner has other duties, as has the pilot of an airplane, he cannot take the time and effort necessary to manually free and charge the gun. These and other considerations make it desirable to have a power mechanism for charging guns, and this mechanism is most desirable when operated automatically.

Attempts have been made to provide power systems to charge guns by using various pneumatic power systems. Some of the pneumatic systems are automatic, using electrical controls to create an automatic action. Invariably, however, in these systems there is a mechanical time lag mechanism, such as a dash pot, which is reset at every shot of the gun. If the gun should fail to fire for a given period of time the dash pot will travel through its stroke and set the charging system in action.

Our invention improves upon the prior art in that it uses hydraulic fluid rather than a pneumatic fluid as the power medium for charging guns. Hydraulic fluid has been found to be more

2

reliable and positive in action and therefore is preferred over pneumatic systems. There are many special problems involved in the use of a hydraulic fluid as compared to a gaseous fluid. Whereas a gaseous fluid may be exhausted to atmosphere, return lines must be provided for hydraulic fluid. Further, valves must be designed to return exhaust fluid to a reservoir, as well as to supply fluid under pressure.

10 Our invention further differs from the prior art in that electrical controls completely regulate the hydraulic charging system. The electrical control circuit is believed to be an improvement over any prior device and is believed to be distinctly novel. In our invention, the time lag mechanism is electrical, thereby saving weight. Also, when compared to a dash pot, there is an increase in service life as a dash pot is subject to abusive operation at every shot. The various 15 parts of the system are particularly designed for a hydraulic system, to accommodate the peculiarities of flow of a hydraulic fluid. In addition to the above, according to one very important feature our invention incorporates a selector valve 20 mechanism for charging several guns from a single master valve.

There are many important parts to the invention. These include a specially designed charging cylinder for hydraulic fluid. Also, special brackets are provided to hold charging cylinders to the guns. We further provide charge counting devices to limit the number of charging operations of a gun, as a gun requiring a large number of such operations has probably expended its 25 ammunition or is in some way defective. Means are provided whereby the armorer of a gun may reload the gun with a fresh belt of ammunition or test the operation of a gun when it is equipped with our charging system. Also, we provide a cut-out means for stopping "runaway" guns, which might otherwise be injured by a long burst of fire.

It is therefore an object of our invention to provide an electro-hydraulic charging system 30 which is fully automatic.

It is a further object of our invention to provide an automatic charging system which meets all conditions and requirements of operation of a gun.

35 Another object of our invention is to provide a charging system for several guns, wherein selector valves direct hydraulic fluid from a single master valve to the particular guns requiring charging.

40 45 50 55 Another object of the invention is to provide

a quick acting solenoid-operated hydraulic valve, having a positive seal in the closed position and operable by a small electric current.

Another object is to provide a charging cylinder for use with hydraulic fluid.

Another object of the invention is the provision of means whereby the armorer of a gun equipped with our invention may reload a gun with a fresh belt of ammunition or test the operation of the gun.

Another object is to provide charge counters which cut out a charging system after a predetermined number of charges.

Another object is to provide means to stop "runaway" guns which fire regardless of trigger actuation.

A feature is to provide special brackets for holding a charging cylinder to a gun, which brackets may be quickly opened to remove a charging cylinder from a gun.

Other objects and features of the invention will be apparent in the following description and claims which may best be understood when considered in connection with the following drawings, in which:

Figure 1 is a diagrammatic plan view of the entire automatic charging system as applied to a pair of machine guns;

Figure 2 is a diagrammatic plan view of a modified form of an automatic system employing selector valves for each charger;

Figure 3 is a view in vertical section of a charging cylinder and a cooperating switch and mechanical charge counter forming a part of our invention;

Figure 4 is a fragmentary outline view showing the switch of Figure 3 in an inoperative position;

Figure 5 is a vertical section along the lines 5—5 of Figure 3 showing the construction of a clamp which holds the charging mechanism to a gun;

Figure 6 is a view in longitudinal section of the solenoid-operated hydraulic valve used with the system; and

Figure 7 is an end view of the piston of the charging device.

Description of the system of Figure 1

The embodiment of our invention shown in Figure 1 will first be described. Two guns 21 are the guns controlled by the accompanying electro-hydraulic system. Although two guns are shown to disclose the application of the invention to a plurality of guns, the invention is equally applicable to a single gun. Also, the invention can be used to control a larger number of guns, and this is implied from the application of the invention to two guns as in Figure 1. The guns may be on an airplane in a turret, or placed in the wings. Or the guns may be in a tank, ship or land fortification or any other place where guns are needed. The use and application of the guns forms no part of the invention.

Our invention employs a hydraulic charging circuit operated by electrical controls. Hydraulic fluid is stored in a reservoir 10 and flows from there to a pump 12 which forces hydraulic fluid under pressure into an accumulator 14, which charges high pressure line 16 with high pressure fluid. Low pressure line 15 returns exhaust fluid to the reservoir. The fluid flow is regulated by solenoid operated valves 18 which direct hydraulic fluid through conduits 19 to charging cylinders 20. The hydraulic fluid acting in cylinders 20 charges the guns 21 to which the cylinders are

attached, and when the charging stroke is completed valves 18 automatically exhaust the charging fluid, completing the charging stroke.

The electrical controls are designed to meet the many requirements of military operations. If during a firing period, a gun becomes jammed, the charging cylinder 20 must be operated to once more place the gun in an operative condition. If the charging cycle is started and the firing period is ended, the charging should nevertheless be continued so that the gun will be ready to fire the next time the trigger is actuated. In the event that a gun starts firing continuously because of some defect, regardless of trigger operation, the charging mechanism must be operable to charge the gun to prevent the "runaway" gun from being injured, or from firing indiscriminately. Another contingency that must be provided for is that of a defective gun which will not fire. If such a gun were charged repeatedly during the firing period it might reduce the fluid pressure available, and means must be provided to cut out the charging mechanism after a given number of strokes. These and other contingencies are all provided for in our system here described.

The electrical circuits of Figure 1 will now be described, and for purposes of simplification will be described with relation to one gun. Corresponding circuits having the same reference numerals can be traced for the other gun. Electrical current under a potential may be derived from any suitable source, but as illustrated, a storage cell 22 is employed. The current passes to an ignition switch 24, which when closed passes current to a slow release relay 26 by means of an electrical conductor. A branch of this electrical conductor passes current to switch 34, which when closed passes current through an electrical charge counter mechanism 300 and through that unit to solenoid valve 18. Thus when switch 24 is closed, current will pass to switch 34, which when closed will pass current to the hydraulic valve 18 which will cause the hydraulic charging mechanism to operate.

The control of the charging mechanism is effected by making and breaking switch 34, and the electrical circuits to accomplish this end will now be described. The circuit through slow release relay 26 has two branches leading to ground. Interposed between the relay 26 and the branches is a manually operated switch 31. One ground branch for relay 26 is through the switch 38 placed at the rear of the gun. Switch 38 is normally open, but is closed by a breech pin on the breech bolt of the gun 21, when the breech bolt reciprocates in the gun. The breech bolt reciprocates in the gun during automatic firing, or when the charging mechanism retracts the breech bolt of the gun in a charging cycle. The other branch ground circuit for relay 26 is through a normally open type of switch 28, which is held closed by the breech bolt when it is in its forward position of the gun, and through switch 30 which is normally closed. Switch 28 is at the forward end of the path of reciprocation of the breech bolt of the gun 21. The breech bolt pin will keep switch 28 closed whenever the breech bolt is closed, but when not closed by the breech bolt it tends to open. Thus, when the breech bolt is closed there will normally be a ground circuit for relay 26 through switch 28 and 30. Grounding relay 26 energizes its solenoid 27, which actuates a bell crank 29 to open switch 34, cutting off any current to valve 18. Thus when switch 24 is

closed, and the breech bolt of the gun 21 is closed, the relay 26 will be grounded and will actuate bell crank 29 to open switch 34 before any appreciable amount of current can reach the valve 18. The only effect then of closing switch 24 will be to open switch 34 when the breech bolt is in a closed position.

Closing switch 24 also passes current to one contact of safety or combat switch 40. When safety or combat switch 40 is closed current is passed to one contact of trigger switch 42. Closing trigger switch 42 passes current to a solenoid operated trigger actuator 44 mounted on the gun 21. This trigger actuator will actuate the trigger of the gun 21 and cause the gun to fire if there is a live shell in the firing chamber. Closing trigger switch 42 also passes current to a solenoid 46 which acts through a bell crank to open switch 30 in one of the ground branches of relay 26. Thus, when trigger switch 42 is closed the ground circuit of relay 26 through switches 28 and 30 is broken at switch 30, and the solenoid 27 of relay 26 starts to lose its energy. However, relay 26 is a slow release relay and will hold the bell crank 29 to keep switch 34 open, during the particular time period for which it is constructed. This period can be any period longer than the time between shots of gun 21 when firing automatically. When the breech bolt upon firing reaches the rearward end of its stroke, the breech pin touches a switch actuator 36 to close switch 38, grounding relay 26 through this circuit which again reenergizes the solenoid 27 of relay 26. This intermittent energization of relay 26 through switch 38 maintains switch 34 in an open position so that valve 18 will not be operated.

If the gun should jam, however, relay 26 would not be intermittently energized through switch 38, and at the expiration of the time period necessary for it to lose its energy it will release bell crank 29 closing switch 34 and passing current through the counter 300 to the valve 18, actuating the hydraulic charging mechanism. When the charging mechanism moves the breech bolt to its most retracted position, switch 38 is again closed and current passes through solenoid 27 of relay 26. The solenoid 27 then attracts one arm of bell crank 29 to again open switch 34 and deenergize solenoid valve 18 causing it to close and communicate the charger 20 to exhaust. When the breech bolt again closes the gun will continue to fire automatically.

If a charging cycle should be started and the firing period then terminated, the gun will nevertheless continue to charge. When the firing period ceases solenoid 46 will be deenergized, allowing switch 30 to close, thus closing one link in one ground circuit of relay 26. However, as soon as the charging cycle starts switch 28 opens, thus opening the only possible ground circuit and the charging operation will continue until switch 38 is closed at the end of the charging movement. Thus one purpose of switch 28 is to continue a charging stroke when the firing period ceases after charging starts. This function could also be served by a switch normally closed, but opened by a charging movement of the charger itself.

Electrical counter unit 300 is provided to limit the number of charges for one gun, as a gun which requires a large number of charges has expended its ammunition or is probably defective. This counter 300 comprises a plate member 302 having a conductor sector and having notches along the edge of another sector. The member 302 is pivoted at 306 about which point it rotates. Brushes 75

304 contact the conductor sector of the member 302. A ratchet arm 308 is also attached to pivot 306 and has a catch 310 pivotally secured thereto, contacting the notches of the member 302. A solenoid 312 receiving current from the main line to valve 18 is placed adjacent to the other end of ratchet arm 308. Every time the valve 18 is energized, current passes through the solenoid 312 to ground, and solenoid 312 acts on ratchet arm 308 to cause rotation through a small arc. The catch 310 on lever arm 308 contacts the notches of member 302 to rotate that member through a corresponding arc. In the meantime the main current passes through brushes 304 and through the conductor portion of member 302 to energize valve 18. After a predetermined number of charges, a conductor sector of the member 302 will rotate out of contact with the rearward brush 304, and thus effectively break the circuit to valve 18. In this way a gun which has expended its ammunition or which repeatedly jams, will not be charged after a predetermined number of charges have already been made.

Switch 31 is manually operable by means of a handle placed on one member of the switch. By holding switch 31 open current cannot pass through relay 26 and any energy therein will be dissipated thus closing switch 34, effecting a charge as described above. By means of switch 31 the gunner may charge any gun if he has any reason to doubt that it is not in an operative condition, or if there is a "runaway" gun this gun may be effectively stopped by opening switch 31, which also causes any gun to be charged. By holding switch 31 manually open the associated gun will charge and the breech bolt will be held in a retracted position, and if the object in so doing is to cool off a "runaway" gun this switch can be kept manually open until such a gun is cooled to the point where another burst of firing will not injure the gun.

A ring 23 is provided for actuating one member of switch 28. This ring is used by the armorer when reloading the gun with a new belt of ammunition. The old belt of ammunition is first manually removed from the gun. By pulling on ring 23, the ground of relay 26 will be broken, and if the pull is of a duration long enough to allow relay 26 to deenergize before releasing ring 23 current will thereby pass to the solenoid of valve 18 to effect a charge which will eject the live shell in the firing chamber. The first link in a new belt is then inserted in the feedway of gun 21 and ring 23 again pulled as before, allowing the gun pawl to engage the first live round. Following these operations, one more charging cycle must be performed before the gun will fire. This charge is usually performed by the gunner, just prior to combat by manually opening switch 31. This charging sequence is followed to provide an added safety feature. Charging ring 23 makes possible the reloading of the gun while performing a minimum of manual operations upon it.

The details of construction of the charging cylinder 20 and the hydraulic valve 18 will be later described, as well as the construction of the brackets which hold the charging cylinder 20 to the gun 21.

Description of the system of Figure 2

The selector valve system shown in Figure 2 will next be described. The selector valve system differs from that of Figure 1 in that each charging cylinder 20 has a selector valve 110 controlling fluid flow from a single master valve 18. The se-

lector valves 110 are connected to a common hydraulic fluid line 19 controlled by master valve 18 and are selectively opened to charge the proper gun. The selector valve system is used to eliminate the weight for each charging cylinder of a separate hydraulic valve strong enough to control fluid under full pressure. The selector valve 110 is opened only when there is no fluid pressure in the line to the charging cylinder 20, and therefore can employ a very small and lightweight solenoid 111. In some installations there is a saving of weight by the use of selector valves, making the system very desirable in such installations, as in aircraft.

The electrical circuit for the selector valve system is basically the same as that for the directly operated system. Closing switch 24 passes current to relay 26, which as in Figure 1 has two ground circuits, one through switch 33, and the other through switches 28 and 30. Solenoid 27 when energized acts through a bell crank 118 to open switch 34 to master valve 18 in much the same way as in Figure 1. Bell crank 118 differs from bell crank 29 of Figure 1, however, in that it is a conductor of current, passing current through its length when switch 34 closes. The other end of a bell crank 118 also forms a part of a switch 120 at the same time it operates a switch 34. When solenoid 27 of relay 26 is de-energized, and bell crank 118 is released, current flows from switch 34 to master valve 18 and in addition through bell crank 118 to switch 120, and through a conductor to the solenoid 111 of selector valve 110. Thus when the solenoid 27 is deenergized, current is passed to selector valve 110, and to master valve 18.

The selector valve 110 is a simple solenoid lift valve or poppet valve of any suitable construction. The solenoid 111 employed is so small, that means must be provided to insure that there will be no pressure on the line 19 when it is operated as any interfering forces cannot be overcome by the selector valve solenoid 111. This means includes a switch 114 for grounding the master valve 18, which switch is operated by the opening movement of selector valve 110. A movable valve core 112 of solenoid valve 110 actuates a bell crank 116, the opposite end of which opens and closes the switch 114 which grounds master valve 18. This construction insures that selector valve 110 will always be open before fluid under pressure is directed to it by master valve 18.

The selector valve system employs mechanical charge counters, and these will be next described, along with the charging cylinder 20. The electrical counters 390 of Figure 1 could also be applied, and could be inserted in the selector valve circuit with equal effect. The mechanical charge counters could also be applied to the system of Figure 1, with equal effect.

Description and operation of the device of Figures 3 and 4

The charging cylinder 20 used with the systems of Figures 1 and 2 is shown in detail in Figures 3 and 4 and will next be described. Although this charging unit is well suited for the automatic systems here described, it is applicable to any type of gun charging system and is not limited to any specific system. The unit may be used on a manually controlled system, and for such use none of the electrical features of the present systems would be used. A manually controlled system in which this unit could be used is described in the copending application by

White and Pontius Serial No. 311,978, filed January 2, 1940. The charging cylinders can also be used in a semi-automatic system such as described in an application by Pontius Serial No. 319,925, filed February 20, 1940. Other uses and applications of the charging unit can be made, and we do not intend to limit its use to the present systems.

The cylinder unit 20 comprises a cylindrical casing 150 within which a cylindrical piston 152 reciprocates. The right hand end of the unit is toward the front of the gun on which it is mounted, and the left end of the unit is secured to the rear of the gun. The piston 152 is provided with means such as a lug 153 which contacts a breech pin 184 (shown in dotted outline) and moves the breech bolt of the gun 21 rearward by acting on breech pin 184 during a charging stroke. The cylinder 150 is slotted at 151 to accommodate the lug 153 which reciprocates with the piston. Fluid flow is directed into the cylinder 150 by a fitting 154 which may be connected to either a selector valve 110 as in Figure 2 or directly to the valve line 18 as in Figure 1. The cylinder 150 is held to the gun by a forward bracket 156 and a rear bracket 158.

The piston 152 is held in a forward position by a compression spring 160 which fits inside cylinder 150 and extends into piston 152. The spring 160 is mounted on a two-part tubular telescoping spring guide. One part of the spring guide is an outer member 162 which is secured to the cylinder 150 by a fitting 164 at the rear end of cylinder 150. The other part of the spring guide is an inner tubular member 166 secured to the piston 152. As the piston 152 reciprocates within cylinder 150 under the influence of hydraulic fluid and the return spring 168, the inner member 166 secured to the piston 152 telescopes in the stationary outer member 162.

A pointed pin 168 slides in guide member 162 and has an extended shank 170 which passes through a constriction in the inner end of guide member 166, and has a head 172 attached to the end of the shank. The relationship of parts is such that the last portion of the rearward movement of piston 152 causes the inner telescoping member 166 of the spring guide to contact the pin 168 and move it rearward. The last part of the forward movement of piston 152 causes the constricted end of guide tube 166 to act on the head 172 of pin shank 170 to pull the pin 168 forward.

These movements of pin 168 cooperate with a breech bolt catch to hold the breech bolt in a retracted position after the charging stroke until the piston 152 has returned nearly to its starting position, giving the breech bolt a free path of travel. The breech bolt catch includes a rocker arm 174 pivoted at 175 to the rear support bracket 158. It comprises a forward end 176, and a rearward portion 178 connected by an intermediate portion 179. On the forward end 176 of the rocker arm 174 is a catch finger 176a pivoted at 176b and urged by a leaf spring 176c to a "catch" position. On the rear end 178 of the rocker arm 174 is a roller 178a designed to reduce friction when the rocker arm is contacted by the pin 168. Also secured to the rear end 178 of rocker arm 174 is a leaf spring 180 contacting the bracket 158. The leaf spring 180 normally maintains the rocker arm 174 in a disengaged position. The fitting 164 on the rear end of cylinder 150 has secured thereto a roller 182 to pro-

vide a thrust bearing when the pin 168 strikes rocker arm roller 178.

The operation of the charging unit as thus far described is as follows. Charging fluid from any suitable control device, manual or automatic, flows through fitting 154 into the cylinder 150. The fluid under pressure forces piston 152 to the left and in doing so the breech bolt of the gun is moved backward through contact of piston 152 with the breech pin 184, shown in dotted outline. As the piston 152 nears the end of its stroke, the guide tube 166 strikes the end of pin 168 forcing it between rollers 182 and 178. This movement of the pin 168 forces the rocker arm 174 to move against the compression of spring 160 to assume a nearly horizontal position. In that position the latch 176 is in the path of the breech pin 184 as shown by the dotted outline of latch 176. As the breech pin nears the end of the charging stroke, it strikes the latch 176 and causes it to rotate about its pivot against leaf spring 176c allowing the breech pin 184 to pass. Once the breech pin is past the latch 176 the spring 176c causes the latch to snap back to its normal position, locking the breech pin in its retracted position.

When the charging cylinder reaches the end of its stroke the charging fluid is cut off from pressure and ported to exhaust, either automatically or manually. Spring 160 now forces the piston 152 to its starting position, forcing out the fluid to exhaust. The latch 176 on rocker arm 174 holds the breech bolt through pin 184 in a retracted position until the piston 152 is out of the path of travel of the breech pin 184 so as to allow the breech bolt to have an unimpeded action on the closing stroke. The release of the breech pin 184 is accomplished by pulling pin 168 from between rollers 182 and 178, which removal allows rocker arm 174 to rotate about its pivot to render the latch 176 inoperative. The pin 168 is pulled from between the rollers by the restriction of tube 166 striking head 172 on shank 170 of pin 168 as the piston 152 is moved to its starting position by spring 160. The arrangement of parts is such that the pin 168 is pulled out from between rollers 178 and 182 only when the piston 152 has retracted out of the path of travel of breech pin 184. As described, the device is a charging unit which will hold a breech bolt in a retracted position until the charging piston has withdrawn from the path of travel of the breech pin.

The charging unit as applied to the systems herein described incorporates further features. The actuator switch 38 is also shown in detail in Figure 3. This switch is operated by the switch actuator 36 which is secured to the bottom side of switch 38. At every reciprocation of the breech bolt, whether during automatic firing or during a charging cycle, the breech pin 184 strikes the switch actuator 36 which in turn closes the switch 38a. It will be noted that the switch 38a is of the snap spring type wherein a small movement on one part causes a movement in the opposite direction of the contacts to close the switch 38a.

The charging unit as shown incorporates a mechanical charge counter. Mounted on the rear bracket 158 is an arm 190 supporting a rotatable ratchet wheel 192 which has a segment removed, and a reciprocable spring pressed push button 194. A strip of spring metal 196 is attached to the upper end of the push button and contacts the ratchet wheel 192. The push but-

ton 194 extends into the path of travel of pin 168. At every charging stroke of the charging unit 20 the pin 168 strikes the push button 194 causing it to move upward against the compression of its spring. This causes a rotation of the ratchet wheel 192.

The actuator switch 38 is rotatably secured to the bracket 158 by means of pivot pin 198. Protruding from the rearward side of the pivot 10 point of switch 38 is a finger 200, which contacts the ratchet wheel 192. The entire switch unit 38 is urged in a clockwise rotatable movement by spring 202 coiled about pivot pin 198, one end of which contacts the rear bracket 158 and the 15 other end of which contacts the finger 200. However, the switch 38 is held in a substantially horizontal position by the contact of finger 200 against the ratchet wheel 192. The purpose of the ratchet wheel 192 and push button 194 is to 20 cut out a charging unit 20 from the hydraulic circuits when a predetermined number of charging operations have been made. An excessive number of charging operations indicates that a gun has expended its ammunition or is defective and in any event can not fire normally, and therefore should be cut out from the hydraulic circuits so as not to reduce hydraulic pressure unnecessarily.

The operation of the mechanical charge counter is as follows. At every charging stroke 30 the ratchet wheel 192 will be rotated one notch by the spring metal strip 196 attached to the push button 194 when it is contacted by pin 168, and after a given number of movements, for 35 example seven, the ratchet wheel 192 will be rotated so that the relieved portion or segment is adjacent the finger 200. When the relieved portion reaches the finger 200 the spring 202 causes the entire switch unit 38 to rotate in a clockwise direction, to the position shown in Figure 4. When in this position the switch actuator 36 is beyond the reach of the breech pin 184 and the switch 38a remains continuously in a closed position. To return the gun to normal operation, the ratchet wheel 192 is manually rotated 40 to its starting position, causing switch 38 to once more assume an operative position as shown in Figure 3.

The switch 28 is also shown in Figure 3, and 50 is shown as housed in casing. Switch 28 is operated by a switch operator 28a, similar to operator 36 for switch 38. This operator is contacted by the breech pin 184 in the breech bolt of gun 21, whenever the breech is closed on the 55 firing chamber.

Description of the device of Figure 5

Another part of our invention relates to the brackets 156 and 158 for holding the charging unit to the gun. As shown in Figure 5 which is a section through the rear bracket 158 the bracket is of a type which may be opened to remove the charging cylinder 150 and its internal mechanism from the gun 21. A semicircular locking member 204 is pivoted to the bracket 158 at 206. A clamp member 208 is hinged to the bracket 158 at 210, and acts through screw 212 to clamp the locking member 204 around the fitting 164 of the charging cylinder 150. When 60 it is desired to dismount the charging cylinder 150, screw 212 is unloosened, the clamp swung downward and the locking member 204 swung upward. In this way the charging cylinder 150 may be unfastened from the gun and the gun 65 removed without disconnecting the hydraulic circuit.

cuit. This type of bracket is desirable for removing a gun from its emplacement for repairs, cleaning or replacement, which operations may be performed without disconnecting any hydraulic circuits.

Description and operation of the device of Figure 6

Another part of our invention relates to the solenoid operated master valve 18 used with our automatic systems. This valve is of the pilot valve type, wherein the fluid pressures controlled are applied by a small pilot valve for opening the main valve. The valve 18 is shown in detail in Figure 6 which is a sectional view of the entire mechanism. The valve 18 comprises a casing 220 having an inlet port 222 and an exhaust port 224, which are selectively communicated by the valve mechanism to an operation port 226. A cylinder 228 closed at one end is secured to the left side of the casing 220 by an annular nut 230. A solenoid unit 232 is secured to the cylinder 228 by a bolt 236 acting through nut 234 placed inside of cylinder 228. A main valve member comprises a sleeve 238 which is centrally slotted to form communicating openings. The end of the sleeve toward the solenoid 232 is enlarged as at 240 to form the large sleeve 241, and seats on the casing 220 adjacent to the inlet port 222. A small passage 242 continuously communicates the interior of the large sleeve 241 with inlet pressure, causing cylinder 228 to be filled with liquid.

A pilot valve is provided for valve 18, and the pilot valve when actuated by a relatively small magnetic effort, applies the principal fluid pressure to open the main valve, which requires a relatively large effort. The pilot valve comprises a needle valve 244 reciprocably mounted in the enlarged end 241 of sleeve 238, and is normally seated against the mouth of a passage 245 formed adjacent to the enlargement 240 and communicating sleeve 238 with enlarged sleeve 241. The needle valve 244 is urged toward its seat by a conical spring 246 seated on cylinder 228. Passage 245 is larger than passage 242. The needle valve 244 is slidably held in sleeve 240 by a transverse pin 248 traversing a slot in needle valve 244. The needle valve body 244 is fluted to allow the flow of fluid past it. A stem 250 is pinned to pilot valve 244, and a fluted hammer member 254 is axially mounted thereon, and free to slide axially. A head 252 on the end of stem 250 holds a weak spring 253 under compression against fluted hammer 254. Fluted hammer 254 moves along stem 250 against the compression of weak spring 253, when solenoid 232 is energized, and strikes head 252 of stem 250, pulling pilot valve 244 off of its seat.

The operation of solenoid valve 18 is as follows. The position of the parts of the valve 18 under normal conditions is shown in Figure 6. Sleeve 238 communicates operation port 226 with exhaust port 224. The enlargement 240 of sleeve 238 is seated against the casing 220 effectively sealing off high pressure port 222. Pilot valve 244 is seated on the mouth of passage 240 and prevents leakage into sleeve 238. High pressure fluid enters passage 242 and fills the interior of enlarged sleeve 241, the portion of casing 220 behind or to the left of sleeve 241, and the interior of cylinder 228. The full fluid pressure available at port 222 is exerted on the fluid inside the valve, through passage 242, and the fluid presses against the end of cylinder 228 and against the sleeve 238 to effectively force enlargement 240 of sleeve 238

against its seat in casing 220. Spring 253 forces fluted hammer 254 toward the right.

When the solenoid 232 is energized by any means including the charging systems which have been described, it attracts fluted hammer 254 toward the left. Hammer 254 compresses weak spring 253 and then strikes violently against the head 252 of stem 250 unseating pilot valve 244 against the compression of spring 246. The high pressure fluid within the sleeve 240 then flows through passage 245 to the exhaust pressure in the right hand side of the valve casing 220. Since passage 245 is larger than passage 242, the pressure inside enlarged sleeve 240 will drop and become greatly less than the pressure in port 222. High pressure fluid in port 222 will now act on the enlarged sleeve 240, throwing it rapidly to the left, allowing the slots in sleeve 238 to communicate high pressure port 222 with operating port 226. The same movement of sleeve 238 closes off exhaust port 224. Fluid will now flow from port 222 to operation port 226 and the operated mechanism connected thereto.

When it is desired to close the valve, the solenoid 232 is deenergized, and fluted hammer 254 is no longer attracted to the left. Spring 246 then seats pilot valve 244, which causes pressure to build up behind it, as passage 242 is at all times in open communication with port 222. The fluid under pressure within the left portion of the valve 18 forces the enlarged sleeve 241 against its seat on casing 220, effectively cutting off the flow of high pressure from port 222 to port 223. The same valve movement communicates exhaust port 224 with operation port 226, through the slots of sleeve 238. Spring 253 forces fluted hammer 254 to the right, and the whole valve is once more ready to be operated.

The valve 18 just described is very important where weight is a factor to be considered, as in aircraft use. By means of the pilot valve, a very small electro-magnetic force can be used to control and operate a poppet type valve subject to high pressures. The use of a small electro-magnetic force allows the use of a very small and lightweight solenoid as compared with the relatively huge solenoid which would be required for direct operation. In the control of high pressures, it is important to use a poppet type valve as contrasted to piston type valves, as a poppet type valve is self-seating and self-sealing. It is believed that the pilot valve control and operation of a poppet type valve which has been disclosed is novel and constitutes a distinct improvement in the art.

Operation of the system of Figure 1

The operation of the system shown in Figure 1 is as follows. The hydraulic pump 12 is operated by any suitable source, and pumps hydraulic fluid from reservoir 10 to accumulator 14. The pressure conduit 16 becomes filled with fluid under pressure and the exhaust conduit 15 becomes subject to exhaust pressure. Solenoid valves 18 are now ready to direct hydraulic fluid to conduits 19 when operated by the electrical circuit. Conduits 19 direct the fluid from valve 18 to the charging cylinders 20 to charge guns 21.

The operation of the electrical circuit will now be described with relation to one gun 21, as the operation is identical for the other gun 21. Ignition switch 24 is first closed, passing current to slow-release relay 26 which is normally connected through manual switch 31, which is normally closed, and through switch 28, which is normally

closed by the breech bolt when the breech of the gun 21 is closed and from there through switch 30 which is normally closed when the gun is not firing, and is there grounded. Grounding this circuit energizes the solenoid 27 of relay 26, which acts through bell crank 29 to open switch 34, thus cutting off current to solenoid valve 18. When it is desired to fire the gun, safety switch 40 is first closed, and then trigger switch 42 is closed. The trigger solenoid 44 is operated by the current from switch 42 and the gun begins to fire. At the same time solenoid 46 is energized, which breaks the ground of relay 26 at switch 30.

When the ground relay 26 is broken at switch 30, there is a tendency for the solenoid 27 of relay 26 to release the bell crank 29, closing switch 34. However, relay 26 is a slow release relay having a release period greater than the interval between shots of the gun to which the charging mechanism is affixed. Since the same switch operation that breaks the ground of relay 26 at switch 30 also energizes the trigger actuator 44, the gun 21 will fire at the same time switch 30 is broken, and the breech bolt reciprocates, alternately closing and opening actuator switch 38. Closing switch 38 grounds relay 26, energizing solenoid 27 so that it will continue to maintain switch 34 in an open position.

If the gun jams during a firing period actuator switch 38 remains continuously open because the breech bolt will not reciprocate, and the solenoid 27 of relay 26 becomes deenergized at the end of its time period causing switch 34 to close. Solenoid valve 18 then opens, passing fluid to the hydraulic charging cylinder 20 which charges the gun by retracting the breech bolt of the gun, ejecting the dud shell and inserting a fresh one. When the breech bolt reaches its most retracted position it acts on operator 36 to close switch 38, thereby grounding relay 26 and breaking the connection to solenoid valve 18. If the trigger system is still in a firing condition the gun will once more fire upon the breech bolt closing and contacting the cartridge chamber.

If the firing control is cut off during the charging stroke it is desirable to continue the charging operation so that a fresh cartridge will be in the firing chamber for the next firing period and this operation is as follows. Upon cessation of firing, solenoid 46 is deenergized and switch 30 is thereby closed. Relay 26 is not grounded, however, as the first movement in the charging cycle forces the breech bolt backward opening switch 28. Because switch 28 is open the ground of relay 26 is broken during the charging cycle until the breech bolt reaches the end of its reciprocatory movement, at which time relay 26 is grounded through actuator switch 38, and valve 18 is thereby closed. The charging operation inserts a fresh shell in the firing chamber and the gun is once more ready for firing when the trigger is actuated.

Often when a period of fire is over it is desirable to reload the machine gun 21 by inserting a fresh belt of ammunition into the mechanism of the gun. The old belt is removed from the gun and a new belt inserted into the gun. The charging operations necessary to place a cartridge of the new belt into the gun can be performed by the charging system. The armorer pulls on ring 23, opening switch 28, breaking the connection to ground for relay 26. If ring 23 is pulled to keep switch 28 open for a period longer than the time interval of relay 26, the deenergization of relay 26 will release bell crank 29 closing switch 34, which actuates valve 18, charging the system.

The first charging stroke ejects the live shell in the firing chamber. The first link in a new belt is then inserted in the feedway of gun 21, and ring 23 is again pulled, allowing the gun pawl to engage the first live round. Following these operations, one more charging cycle must be performed before the gun will fire. This charge is usually performed by the gunner, just prior to combat by manually opening switch 31. This charging sequence is followed to provide an added safety feature inasmuch as the gun cannot be fired until this final charge is made.

The electrical charge counter 300 cuts out a gun which requires an excessive number of charges, as such a gun is probably defective, and the operation is as follows. At every charge, solenoid 312 is energized, pulling on ratchet arm 308 which in turn rotates conductor member 302 about its pivot 306. The current meantime flows from brushes 304 through conductor member 302 to operate valve 18. After a predetermined number of charges have been made, the ratchet has rotated conductor member 302 out of contact with the forward brush 304. In this position of member 302, current can no longer pass to valve 18, and thereafter when gun 21 jams it will not be charged, but will remain in a jammed condition. Charge counter 300 can be reset manually to start through its cycle of operation.

In firing a gun it sometimes happens that a part will become stuck or injured so that a gun will continue to fire regardless of trigger actuation. Such a gun is known as a "runaway" gun. Our invention provides means to control such guns to keep them from becoming injured by long continued fire. This means is the manually operated switch 31 illustrated as near relay 26. By manually opening switch 31 the ground connections of relay 26 are all disconnected and switch 34 closes passing current to solenoid valve 18 causing it to charge the gun 21. Often a single charge is enough to restore a runaway gun to normal operation, but where this is not sufficient the breech bolt of the gun can be held in a retracted position by keeping switch 31 open until the gun is cooled to a point where further "runaway" firing will not injure it. The switch 31 is shown adjacent to the gun, but by using longer conductors the switch 31 could be placed near the other manually operated switches 24, 40 and 42.

Operation of the system of Figure 2

The operation of the selector valve system shown in Figure 2 is as follows. Ignition switch 24 is first closed passing current to slow release relay 26 which is grounded through switch 28, which is normally closed by the bolt of gun 21 and from there through switch 30, which is closed when the gun is not firing. Grounding this current energizes the solenoid 27 of relay 26, which acts through a bell crank 118 to open switch 34 and switch 120, thus cutting off current to master valve 18 and selector valve 110. When it is desired to fire the gun, safety switch 40 is first closed, and then trigger switch 42 is closed. The trigger solenoid 44 is operated by current from switch 42 and the gun begins to fire. At the same time, solenoid 46 is energized, breaking the ground of relay 26 at switch 30.

When the ground of relay 26 is broken at switch 30, there is a tendency for the solenoid of the relay 26 to release the bell crank 118, closing switches 34 and 120. Relay 26 is, however, a slow release relay of any suitable time period greater

than the period of automatic fire of the gun 21. Due to this characteristic, relay 26 will hold the bell crank 118 until its time period has elapsed, in the absence of an intervening charging current. Relay 26 is intermittently grounded, however, through actuator switch 38, and the bell crank 118 is thereby held to keep switches 34 and 120 in an open condition, preventing the operation of master valve 18 and selector valves 110. Actuator switch 38 is intermittently closed by the reciprocating breech bolt of gun 21 striking switch operator 38. At every shot of the gun 21, the breech bolt reciprocates and as the time between shots is less than the period of the slow release relay 26, the solenoid of relay 26 will be reenergized before its release period has expired.

If one of the guns should jam during a firing period, the solenoid 27 of relay 26 of the jammed gun becomes deenergized at the expiration of its release period, and the bell crank 118 moves to close switches 34 and 120. Selector valve 110 now opens, and the movement of its core 112 acts through bell crank 116 to close switch 114, grounding the current through the solenoid of master valve 18 which then opens to line 16. The opening of selector valve 110 opens a passage for fluid to flow from the line 19 into the charging cylinder 20. When master valve 18 is operated, high pressure fluid flows into line 19, and through the open selector valve 110 and into the charging cylinder 20 of the jammed gun, charging that gun by retracting its breech bolt for counter-motion, which action ejects the dud shell and inserts a fresh one. During this charging operation, the selector valve of the other gun remains closed, no fluid can enter its charging mechanism, and the gun continues to fire uninterruptedly. When the breech bolt reaches its most retracted position during the charging stroke, it acts on operator 38 to close the actuator switch 38, thereby grounding relay 26 and breaking the connection to selector valve 110 and master valve 18. The charging mechanism exhausts its charging fluid and the gun is again ready for firing. If the trigger system is still in a firing position, the gun will once more fire upon the breech bolt contacting the cartridge chamber.

Upon cessation of firing, solenoid 46 is deenergized, allowing switch 30 to close and establishing a ground for relay 26 through switches 28 and 30. This energizes the solenoid of relay 26 which acts on bell crank 118 to render master valve 18 and solenoid valve 110 inoperative.

If the firing control is cut off during the charging stroke, it is desirable to continue the charging operation so that a fresh cartridge will be in the firing chamber for the next firing period and this operation is as follows. When the charging cycle is started just prior to the cessation of firing, switch 28 is opened, thereby breaking the ground circuit for relay 26 that is normally established upon cessation of firing. Relay 26 therefore remains deenergized, and switches 34 and 120 remain closed. When the breech bolt reaches the end of its charging stroke, it causes switch 38 to close thus grounding relay 26, and causing switches 34 and 120 to open, allowing the charging fluid to return to exhaust. By this operation a fresh cartridge is placed in the firing chamber, and the gun is again ready for automatic fire when the trigger is actuated.

The armorer's charging operation by pulling on ring 23 is similar to that of Figure 1 which has already been described. Also the operation for stopping a "runaway" gun in the system of Fig-

ure 2 is similar to that of Figure 1, which operation has also been described.

Having described our invention it is not intended to be limited to the specific disclosure made. The hydraulic and electrical systems may be changed in many ways and yet fall within our invention. Any fluid could be used in place of a hydraulic fluid in the systems disclosed. The devices included in the system may have various different applications and still come within the scope of the invention. Nor is the invention limited in any way other than by the terms of the following claims.

We claim:

1. The combination with a gun having a reciprocable breech bolt, of a fluid motor mounted on the gun to retract the bolt, a piston in said fluid motor normally urged toward one end thereof, means for engaging the breech bolt for retracting the same upon movement of the piston toward the other end of the motor, means mounted at said other end of the motor for latching the bolt in retracted position, and means within said fluid motor and operative upon movement of the piston toward the said other end of the motor to control the latching means to latch the bolt in retracted position and operative upon movement of the piston toward the said one end of the motor to release the latching means.

2. The combination with a gun having a reciprocable breech bolt, of a fluid motor mounted on the gun to retract the bolt, a piston in said fluid motor normally urged toward one end thereof, means for engaging the breech bolt for retracting the same upon movement of the piston toward the other end of the motor, means mounted at said other end of the motor for latching the bolt in retracted position, and latch controlling means disposed within the motor and including a two-way lost-motion connection with the piston and operative upon movement of the piston toward the said other end of the motor to control the latching means to latch said bolt and operative upon movement of the piston toward the said one end of the motor to control the latch means to release the bolt.

3. The combination with a gun having a reciprocable breech bolt, of a fluid motor mounted on the gun to retract the bolt, a piston in said fluid motor normally urged toward one end thereof, means for engaging the breech bolt for retracting the same upon movement of the piston toward the other end of the motor, means mounted on the motor for latching the bolt in retracted position, and means slidably mounted within said fluid motor and operative upon movement of the piston to the said other end of the motor to control the latching means to latch the bolt in retracted position and operative upon movement of the piston to the said one end of the motor to release the latching means.

4. A mechanism for retracting the breech bolt of a gun comprising a cylinder, a piston in the cylinder, said piston being normally urged toward one end of the cylinder and arranged for reciprocation therein, means for engaging the breech bolt for retracting the same upon movement of the piston toward the other end of the cylinder, means mounted on the cylinder for holding the breech bolt in a retracted position, and means slidably mounted in the cylinder and operative upon movement of the piston toward the said other end of the cylinder to control the holding means to hold the bolt in retracted position and operative upon movement of the piston toward

the said one end of the cylinder to release the holding means.

5. A mechanism for retracting the breech bolt of a gun comprising a cylinder, a piston in the cylinder, said piston being normally spring urged toward one end of the cylinder and arranged for reciprocation therein, means for engaging the breech bolt for retracting the same upon movement of the piston toward the other end of the cylinder, a latch means mounted on the cylinder for latching the breech bolt in retracted position, and latch controlling means carried by the cylinder and slidably mounted with respect thereto and operative upon movement of the piston toward the said other end of the cylinder to control the latch means to latch the bolt in retracted position and operative upon movement of the piston toward the said one end of the cylinder to release the latch means.

6. A mechanism for retracting the breech bolt of a gun comprising a cylinder, a piston in the cylinder, said piston being normally urged toward one end of the cylinder and arranged for reciprocation therein, means for engaging the breech bolt for retracting the same upon movement of the piston toward the other end of the cylinder, means mounted on the cylinder for holding the breech bolt in a retracted position, and means carried by the cylinder and operative upon movement of the piston toward the said other end of the cylinder to control the holding means to hold the bolt in retracted position and operative upon movement of the piston toward the said one end of the cylinder to release the holding means.

7. In a mechanism for retracting the breech bolt of a gun, a cylinder, a piston in the cylinder arranged for reciprocation, means for engaging the bolt for retracting the same upon movement of the piston in one direction, a latch member mounted on the cylinder and constructed and arranged for holding the bolt in retracted position, and latch controlling means slidably disposed within said cylinder and operative upon movement of the piston in said one direction to control the latch member to latch the bolt in retracted position and operative upon movement of the piston in the opposite direction to release the latch member.

8. The combination with a gun having a reciprocable breech bolt, of a fluid motor mounted on the gun to retract the bolt, a piston in said fluid motor normally urged toward one end thereof and constructed and arranged to engage the breech bolt to retract the same when said piston is moved toward said other end of the motor, means mounted on said other end of the motor for latching the bolt in retracted position, and means within said fluid motor and operative upon movement of the piston to the said other end of the motor to control the latching means

to latch the bolt in retracted position and operative upon movement of the piston to the said one end of the motor to release the latching means.

9. A mechanism for retracting the breech bolt of a gun comprising a cylinder, a piston in the cylinder normally spring urged toward one end of the cylinder and arranged for reciprocation therein, means carried by the piston to engage the breech bolt to retract the same upon movement of the piston to the other end of the cylinder, means mounted on said other end of the cylinder for latching the bolt in retracted position, and means within said cylinder for controlling said latching means and including a member constructed and arranged to be extended from the said other end of the cylinder after the piston has retracted the breech bolt to latch the bolt in retracted position and to be withdrawn into said cylinder after the piston has returned to its normal position to release said latching means.

10. A mechanism for retracting the breech bolt of a gun comprising a cylinder, a piston in the cylinder normally urged toward one end thereof, means secured to the piston to engage the breech bolt to retract the same upon movement toward the other end of the cylinder, means mounted on said other end of the cylinder for latching the bolt in retracted position, a member in said cylinder constructed and arranged to be actuated by the piston to control said latching means, said member having a portion extendable from the end of the cylinder to engage said latching means to latch the bolt in retracted position after the piston has been moved to the said other end of the cylinder and a portion engageable by the piston to withdraw said extendable portion into said cylinder after the piston has been moved to the said one end of the cylinder to disengage said latching means to unlatch the bolt.

11. A mechanism for retracting the breech bolt of a gun comprising a cylinder, a piston in the cylinder, said piston being normally spring urged toward one end of the cylinder and arranged for reciprocation therein, means for engaging the breech bolt for retracting the same upon movement of the piston toward the other end of the cylinder, a latch member mounted on the cylinder and constructed and arranged for latching the breech bolt in retracted position, and latch controlling means slidably mounted in the cylinder and operative upon movement of the piston toward the said other end of the cylinder to operate the latch member to latch the bolt in retracted position and operative upon movement of the piston toward the said one end of the cylinder to release the latch member.
